UNITED STATES PATENT OFFICE

LUDWIG G. JACOBSON, OF JAMESTOWN, NEW YORK, ASSIGNOR TO DAHLSTROM METALLIC DOOR COMPANY, OF JAMESTOWN, NEW YORK, A CORPORATION OF NEW YORK

SWING DOOR INCLOSURE INTERLOCK

Application filed June 13, 1929. Serial No. 370,553.

This invention relates to an improvement in door and door inclosures and more particularly to an interlocking mechanism therefor.

5 In its preferred embodiment this invention is directed to an automatically operated interlocking mechanism for swing doors mounted in elevator entrance inclosures. The interlocking structure, although shown as applied to elevator entrance inclosures, is equally applicable to practically all types of swing door inclosures wherein it is desired to automatically engage or release a door at specified times or under certain conditions.

10 Although door inclosures now on the market are provided with various kinds of locking mechanisms and although these structures are in commercial operation, they are not wholly practical from the standpoint of safety, convenience of operation, size, location, and cost of manufacture. In the present trend of elevator entrance inclosure structures, it is essential that doors opening upon the elevator shaft be provided with a locking structure which does not extend into said shaft but is contained within the inclosure. Furthermore, it is essential that the device be of such design and construction as to permit automatic control through the elevator cab. It is most vital in providing a structure of this type that the lock be positive and quick acting or in a sense foolproof in order to pass the inspection of the building underwriters. In producing locking mechanisms containing the above requirements, it is also of great importance to so design the mechanism that it will not be cumbersome and present an unsightly appearance. Present elevator entrance inclosures, and particularly those of the swing door type, are the product of simple and attractive designs and it is therefore essential that the locking structure be absolutely concealed from view and further that when the door is in opened position no unsightly structure is discernible.

15 The principal object of this invention is to provide a swing door entrance inclosure, the interlocking mechanism of which is both positive and quick acting.

20 Another object of this invention is to pro-

vide an interlocking mechanism contained within the walls of the inclosure and door.

A further object of this invention lies in the provision of an interlocking mechanism contained within the walls of the inclosure 55 and provided with automatic mechanical contact with an elevator cab by which to operate said interlock.

A still further object of this invention lies in the provision of an interlocking mechanism 60 requiring no unsightly openings in either the door or inclosure.

Another and further object of this invention is the provision of an automatically 65 operated draw bolt retaining means.

Other and further objects of this invention will be more readily understood from a consideration of the following specification when taken in conjunction with the accompanying drawings; and in which

70 Fig. 1 is a view of an elevator shaft, showing the mechanical contact between the interlocking mechanism of a swing door inclosure unit and an elevator cab;

75 Fig. 2 is a fragmentary view similar to Fig. 1, showing the mechanical travel required to release the interlock of the inclosure from the door;

80 Fig. 3 is a vertical sectional view taken on the line 3—3 of Figure 5, showing certain details of the interlocking mechanism including the make and break contacts of the elevator cab current supply;

85 Fig. 4 is a fragmentary vertical sectional view similar to Figure 3, showing the position of certain of the interlock elements when the swing door is released;

90 Fig. 5 is a front elevation of the interlocking mechanism, parts being broken away to better disclose certain details of construction;

95 Fig. 6 is a horizontal sectional view taken substantially on the line 6—6 of Figure 5 and shows the interlocking draw bolt in engaged position;

Fig. 7 is a sectional view similar to Figure 6, showing the draw bolt of the swing door in released position;

100 Fig. 8 is a sectional view similar to Figure 7, showing the relative position of the inter-

locking elements when the swing door is moved away from the inclosure as well as the means for holding the draw bolt in retracted position within said door;

5 Fig. 9 is a vertical sectional view of the draw bolt retaining mechanism being taken substantially on the line 9—9 of Figure 5;

10 Fig. 10 is a vertical sectional view of the interlocking elements as shown in Figure 7 and is taken on the line 10—10 of this figure;

15 Fig. 11 is a plan view of the structure mounted upon the elevator cab by which contact is made with the interlocking mechanism, being taken substantially on the line 11—11 indicated in Figure 1;

20 Fig. 12 is an enlarged horizontal sectional view, taken substantially on the line 12—12 of Figure 1, and discloses details of construction of the contacting structure of the 25 interlocking mechanism with the cab;

Fig. 13 is a vertical sectional view taken substantially on the line 13—13 of Figure 6 and shows the cab current supply switch in operating position;

25 Fig. 14 is a fragmentary vertical sectional view of a modification of the interlock actuating cam taken on the line 14—14 of Figure 15;

30 Fig. 15 is a plan view of the structure shown in Figure 14.

Figure 16 is a vertical sectional view taken substantially on the line 16—16 of Figure 7; and

35 Figure 17 is a schematic wiring diagram of the hoisting motor control circuit.

Referring to the drawings and particularly to Figure 1 thereof, this invention is preferably shown for use upon an elevator entrance inclosure generally indicated by the 40 reference numeral 10. The inclosure 10 forms one of the walls of the elevator shaft 11 in which is located, for purposes of structural illustration, a cab 12. Mounted upon the cab 12 is a solenoid 14, having a movable armature 15 therein. A link 17 is joined by the pivotal connection 18 to one end of the armature 15. The other end of the link 17 is pivotally connected at 20 with a channel member 21. The channel member is formed 45 with side walls 22, along one of which bosses 23 are formed and to which channel supporting links 25 are pivotally mounted upon said bosses. The links 25 are pivotally supported upon the cab 12. It is to be noted that the armature 15, in the position shown in Figure 1 of the drawings, when assisted by the links 17, supports the channel member 21. When 50 energy is cut off from the solenoid 14, the armature 15, due to the weight of the channel member 21 and links 17 and 25, moves by gravity to the position shown in Figure 2 of the drawings. The downward movement of the armature and the links 25 is limited in any suitable fashion as by the provision 55 of a stop pin 26 mounted on the cab.

The purpose of the structure mounted upon the cab 12 is to facilitate and control lateral movement of the channel member 21 toward or away from the entrance inclosure. When current is supplied to the solenoid 14, the 70 armature is drawn thereinto raising upwardly as well as moving laterally the channel member 21.

Mounted within the inclosure 10 is a box-like structure 28 which contains the interlocking mechanism. The box 28 is set into the inclosure 10 and secured thereto in any suitable manner. The shaft wall 31 of said box has supported thereon the entire interlocking mechanism. The reason for this is to permit the quick removal and repair or replacement of any of the elements of the interlocking mechanism should failure for any reason occur. The wall 31 is in the form of a cover to the box 28 and is secured thereto by bolts or in any other accepted manner. Mounted on the wall 31 of the box 28 is a boss 29 having spaced lugs 30. These lugs are horizontally drilled to permit the passage therethrough of the bolt 32. The interlock operating cam 34 is comprised of adjustable telescoping elements 36 and 37, secured together by bolts 38. The element 36 of the cam, adjacent its inner end, is formed with an enlarged portion 39 through which 85 an opening 40 is drilled and in which a keyway 42 is formed. The portion 39 is mounted against the outer face of one of the lugs 30 of the boss. Between the lugs 30 and keyed to the bolt 32 is an arm 41. This arm 90 extends through a slot in the wall 31 into the box 28 and is directly connected with the interlocking mechanism. The arm 41, being connected through the bolt 32 to the cam 34, transmits any movement of said cam to the 95 operating mechanism contained within the box. The outer end of the element 37, which forms a part of the cam 34, is drilled to permit the passage therethrough of a bolt 44 upon which is mounted a roller 45. The roller 45, being mounted upon the end of the cam 34, extends well into the elevator shaft 11 and is in vertical alignment with the channel member 21 when said channel member is in the 100 position shown in Figure 1 of the drawings. When the cab 12 moves upwardly or downwardly past a floor level, from which inclosure the cam 34 projects, the roller 45 passes between the walls 22 of the channel member 21. It will be noted that the ends 105 of the walls 22 are slightly flared to assist in centering the roller for free passage through the channel member 21. When the elevator cab 12 stops at a floor level, the roller 45 will lie within the channel member 21 substantially as is shown in Figure 1 of the drawings. When installing the contact structure on the cab, infinite care as to location need not be taken in view of the fact that the cam 34 is telescopically adjustable 110

115

120

125

130

and may be moved in order that the roller 45 will center between the walls of the channel member 21.

At this point in the description attention 5 is directed to Figures 14 and 15 in which is shown a slight modification of the interlock operating cam above described. The modified cam 47 is comprised of telescopedically engaged elements 48 and 49. Secured to the 10 end of the element 49, by means of a pin 50, is a roller 51 which corresponds to the roller 45. The element 48 is formed with flanges which engage the element 49 and suitable bolts 53 join said elements together. Adjacent 15 its inner end, the element 48 is mounted between plates 55 and 56. These plates are secured to the wall 31 of the box 28 by means of bolts 57. Concentrically disposed horizontal openings 59 are formed in the plates 20 55 and 56 by means of and between which the element 48 is pivotally secured by a pin 60. The element 48 terminates in an angle portion 62 which extends into the box 28 and is connected with the interlocking mechanism. 25 Within the box 28 and secured to the wall 31 of said box is an angle bracket 66, having an opening 67 drilled through its horizontal flange 68. A plate 70 is supported in the opening 67 of the bracket 66. Encircling 30 the plate 70 is a coiled spring 71, the upper end of which abuts the lower face of the flange 68. The lower end of the spring is supported upon a shoulder 72, securely attached in any suitable manner to the plate 35 70. Directly beneath the shoulder 72 a slotted opening 74 is formed with which the arm 41 of the operating cam engages. When the cam 34 is moved toward or away from the box 28, the arm 41 causes a vertical reciprocation of the plate 70. Adjacent the lower 40 end of the plate 70, an opening 76 is formed. This opening is in the form of a slot arranged at a substantial angle to the longitudinal axis of said plate. In order to support the 45 plate and prevent all but a vertical reciprocation thereof, a strap 77 incloses the lower end of said plate. The flanges 78 of said strap are welded or otherwise suitably secured to a second strap 80. The strap 80, 50 by means of flanges 81, is welded or otherwise joined to the wall 31 of the box 28 through a supporting plate 82. The strap 77, supporting the vertical plate 70, is at right angles to the strap 80 which is adapted 55 to support the horizontally movable elements.

Between the strap 80 and the plate 82 is mounted a horizontal guide member 84, the flanges 85 of which are permanently joined 60 to the plate 82. The raised portion 86 of the guide 84 abuts the raised portion of the strap 80. Supported within the guide 84 is a draw bolt engaging element 88, the outer end 89 of which is formed to provide a pocket 65 91. One of the walls 92, of the pocket 91,

terminates in a finger 93, the purpose of which will later be brought out. That portion of the element 88 located within the guide member 84 is provided with a drilled and tapped opening 95 into which is threaded a bolt 96. Between the enlarged head 97 and the threaded portion, said bolt is fitted with a bushing 98. The bushing 98 is of a diameter such that it will freely enter the opening 76 of the plate 70.

The straps 77 and 80 are formed with concentrically disposed horizontal slots 99 and 101 respectively. The guide 84 is likewise formed with a slot 102 concentrically disposed with the slots 99 and 101. and when said bolt is in the position shown in Figure 7, the recess 119 is in line with an opening 120 in the vertical wall of the bracket 113. Mounted upon a supporting plate 122 is 5 a pivot arm 123, joined to said plate by means of a pin 124. The inner end of the arm 123 terminates in a finger 126 which is adapted to pass through the opening 120 of the bracket 113 and engage the draw bolt by means 10 of the recess 119. A flange 127 is struck up from the plate 122 directly to the rear of the finger 126 and a coiled spring 128 is mounted between said flange and said finger. The purpose of the spring is to cause the finger 126 15 to, at all times, engage the draw bolt 112, either along the vertical face thereof or within the recess 119. As may be seen in Figure 8 of the drawing, were it not for the arm 123 engaging the draw bolt 112, when the door 20 106 is opened, said draw bolt could move out of the door and, as the door closed, would strike the enclosure preventing a complete closing and the subsequent locking of said door. The end of the arm 123, remote from 25 the finger 126, terminates in a curved flange 130 which is engaged by the end 89 of the element 88 when the door is closed. The arm 123 therefore is held out of engagement with the draw bolt 112 against the tension of 30 the spring 128 by the end 89 of the element 88. When the door is opened, the arm 123 is freed of contact with the end 89 and the spring 128 causes the finger 126 to engage the recess 119 of the draw bolt 112. 35 Adjacent the jointure of the arm 117 with the body portion of the draw bolt 112 and in the vertical face of said arm a recess 132 is formed. Permanently mounted within the recess 132 is a copper or other efficient current carrying contact 133. Within the box 28 is a switch 135 comprised of an actuating arm 137 formed from a suitable insulating material and of a configuration substantially 40 that shown in Figure 6 of the drawings. The end of the arm 137 is formed with vertically spaced recesses 138 in which are mounted spaced copper contacts 140. The contacts 140 form an open circuit and the contact 133 of the arm 117 is adapted to close this circuit 45 which is employed to control the operation of the solenoid 14 mounted upon the elevator cab 12. 50

The inner end of the arm 137 is formed 55 with a vertical slot 141 in which is permanently located a metal insert 142. Mounted above and below the arm 137 and secured within the switch box 135, by means of threaded elements 144, are spring supported 60 contacts 146. These contacts are provided with heads 148 formed at the end of rods 149. The end of the rod is supported within an opening provided therefor in the element 144. A spring 151 encircles the rod 65 149 between the head 148 and the element

144, causing said contact to engage the arm 137 under spring pressure. Suitable terminals 152 by which electrical connection is had with the contacts 146 are formed at the end of each rod 149. It may readily be 70 understood that when the arm 137 is mounted between the head 148 of the contacts 146, said contacts will open or close the circuit in which they are located as said arm moves in or out by reason of the fact that they engage either 75 the insulating material, of which the arm is formed, or the metal insert 142. The circuit, which is opened or closed by the above described switch structure, controls the power 80 by which the elevator cab is raised or lowered. Attention is directed to the fact that the contacts 146 and metal insert 142 control current supply to the cab 12 and contacts 140 and 133 control the current supply to the 85 solenoid 14. The source of current supply to the cab is the same as that to the solenoid although they are controlled by different intermediate switches. It would follow therefore that if the cab power is turned on, it is 90 possible for either the solenoid 14 or the cab to function independently of each other or under certain conditions to function together. The purpose of this switch control will be clearly brought out in the description 95 of the operation of the device. 95

In assembling a device of this character, it has been found preferable to unite certain groups of elements prior to the final assembly of the entire mechanism. For this reason, the switch structure 135 is assembled 100 as a unit and, after the interlocking structure has been mounted upon the wall 31, said switch is installed. The cam 34 and cam support, being also mounted upon the wall 31, are assembled with the interlocking structure when said wall is secured to the box 28. The cab structure is next secured in place, the channel 21 thereof being moved to 105 approximate alignment with the inoperative position of the roller 45. When this is done, any slight misalignment, as between the roller 45 and channel 21, may be overcome by shortening or lengthening the cam 34. 110

In describing the operation of this invention no particular reference is made to the various controls mounted in the pent house in the top of the shaft nor to any other switch operating structures other than those above described for the reason that these structures are old and well known in the art. For the purpose of illustration, let it be assumed that the cab 12 has just moved to the floor level indicated in Figure 1 of the drawings. During this movement current is acting to energize the solenoid as well as operate the cab. As the cab operating power is cut off, the power to the solenoid 14 is likewise cut, thus permitting the armature 15 therein to move 115 outwardly by force of gravity carrying with 120 the switch structure 135. 125

it the channel member 21. The movement of the channel is transmitted to the roller 45 with which it is engaged and causes said roller and the cam 34 to move downwardly 5 toward the inclosure 10. Since the cam 34 and arm 41 are keyed together through the shaft 32, said arm will be raised a distance proportionate to the downward travel of said cam. Because the arm 41 is engaged 10 with the plate 70, through the opening 74, said place will move upwardly compressing the spring 71, this upward movement causing the bolt 96 to move laterally within the angularly cut slot 76. In as much as the bolt 15 96 is secured to the element 88, said element will move toward the door 106.

For a clearer understanding of the operation about to be described, reference is had to Figures 6, 7 and 8 of the drawings. The 20 outer end 89 of the element 88 is engaged with the arm 117 of the draw bolt 112 by means of the pocket 91. Furthermore, the finger 93 forming a part of the end 89 is located to the rear of a shoulder formed in 25 the switch arm 137. Consequently, as the element 88 moves outwardly, the draw bolt 112 will be moved into the door 106, through the slot 116 in said door, and the arm 137 will be moved to the position such that the 30 contacts 146 no longer engage the metal insert 142 but are separated by a part of the insulated arm 137. As the switch 135 is in the circuit which supplies power to move the cab 12, breaking of this contact prevents the 35 cab from being moved away from the floor with which it is in register. The reason for this is obvious, because, when the draw bolt 112 has moved into the door 106, said door is unlocked and may be operated from either 40 side of the elevator shaft. Because no power can be transmitted to move the cab from the floor level, it is safe for the door 106 to be opened or closed as desired.

As brought out in the description of the 45 door 106, it is possible the draw bolt 112, when said door is swung open, might be jarred out of place sufficiently to prevent complete closing of the door. This is prevented by the engagement of the finger 126 under pressure 50 of the spring 128 with the draw bolt. This movement of the pivoted arm 123 occurs only when the door is swung open and by which action the flange 130 is released from contact with the end 89 of the element 88. When 55 the door is again closed, the flange 130 strikes the end 89, causing the finger 126 to move out of engagement with the recess 119 in the draw bolt 112 and said bolt may then be moved into locked position.

60 Attention is directed to the fact that, although the current supply to operate the cab 12 is cut by means of the switch 135, it is also necessary that the current supply for the solenoid 14 be cut at substantially the 65 same time. The reason for this is due to

the fact that the switch by which the cab is moved may be closed and, although the cab will fail to move due to the break in its circuit through the switch 135, the solenoid might operate thus causing the interlocking structure within the inclosure 10 to move to locked position. If it so happened, that the door 106 was even slightly opened at this time, when it closed later no locking thereof would take place and as the cab moved from the floor level said door could be opened upon an unguarded shaft. In order to prevent such a contingency, the current supply in the solenoid 14 is carried through the contacts 140 which are spaced apart from each other in the end of the arm 137 of the switch 135. The end of the draw bolt being fitted with the contact 133 completes or breaks the solenoid circuit through the contacts 140. Therefore, although the cab operating switch may be closed, the solenoid 14 cannot be energized unless the door 106 is in full and complete engagement with the inclosure 10. When the door 106 is closed and the solenoid circuit is completed through the contacts 140, 70 said solenoid will actuate the interlocking mechanism to lock the door and at the same time the arm 137 of the switch 135 will be moved by a pushing action of the end of the draw bolt 112 to a position such that the metal insert 142 completes the circuit between the contacts 146 and thus permits the 75 flow of current to operate the cab 12.

It will be noted that when the cab 12 leaves the floor with which it was in register, no movement or action of the interlocking mechanism takes place by reason of the fact that in order for said cab to be supplied with energy by which to move it upwardly or downwardly, the interlock must have been operated to secure the door. During the travel of the cab 12, between floors or during the time that current is supplied to the cab, the solenoid 14 is energized in order that the 80 armature 15 mounted therein will retain the channel member 21 in its innermost position which is in vertical alignment with the rollers 45 located at the various floors. As the cab comes in register with any floor, the 85 solenoid current is cut simultaneously with the cutting of the current to the cab and since, when said cab is in register with a given floor, the roller 45 is within the channel member 21, said channel member will 90 drop under force of gravity, operating the cam 34 and releasing the interlock of the door 106.

It is to be understood that the weight of the channel member 21 and its attendant 95 links 25 is sufficient to overcome the tension of the spring 71 mounted in the box 28. The purpose of the spring 71 is merely to insure the maintenance of the cam 34 and roller 45 in extended inoperative position in order 100

that as the cab 12 moves upwardly or downwardly the channel member 21 mounted thereon will register with the roller 45. Should it be found necessary, additional weight could be supplied to the channel member 21 by increasing the size of the supporting links or a small spring could be attached to exert a downward and forward pull upon the channel 21 when energy to the solenoid 14 is cut off.

The structure shown in Figures 14 and 15, and dealing with a modification of the cam 47 and roller 50, is operated by the identical structure that the cam 34 and roller 45 are operated. However, in this instance the roller contacting structure is mounted on the face of the cab thereby creating a transverse movement to the channel member 21 and an up and down movement to the cam 47. The angle portion 62 of the cam 47 is engaged with the plate 70 in substantially the same manner as the arm 41 of the cam 34.

Although one modification of the interlocking mechanism has been shown and described and two modifications or adaptations of the contacting structure have been shown, applicant does not intend to be limited thereto since it is obvious to those skilled in the art that other modifications may be made without departing in any way from the spirit and scope of this invention as set forth in the hereunto annexed claims.

Having thus set forth my invention what I claim as new and for which I desire protection by Letters Patent is:

1. In an elevator structure, a locking mechanism for swing door inclosure units comprising extendable means within the frame of said unit, withdrawable means in the door of said unit and further means mounted upon a cab, said last means being adapted to actuate said withdrawable means through said extendable means to control opening said door.

2. In an elevator structure, a locking mechanism for swing door inclosure units comprising extendable means within the frame of said unit, withdrawable means in the door of said unit, said withdrawable means being normally engaged with said extendable means, and means mounted on a cab adapted to actuate said withdrawable means whereby to control opening said door.

3. In an elevator structure, a locking mechanism for swing door inclosure units comprising extendable means within the frame of said unit, means withdrawable from in the door of said unit, said withdrawable means being normally engaged with said extendable means, and a further cab operated means adapted to actuate said withdrawable means to control opening said door.

4. In an elevator structure, a locking mechanism for swing door inclosure units com-

prising extendable means mounted in the frame of said unit, withdrawable means mounted in the door of said unit normally engaged with said extendable means and further means mounted on a cab in the shaft 70 of said structure, said last means being adapted to actuate said extendable means whereby to withdraw said withdrawable means to prevent opening said door.

5. In an elevator structure, a locking mechanism for swing door inclosure units comprising a draw bolt mounted in the door of said unit, means mounted in the frame of said unit normally engaged with said draw bolt and cam means mounted on a cab located within the shaft of said structure, said cam means being adapted to actuate said frame means whereby to move said draw bolt into locked or unlocked position.

6. In an elevator structure, a locking mechanism for swing door inclosure units comprising means automatically actuated by a cab control member, means mounted in the frame of said unit, further means mounted within the door of said unit normally interengaged with said frame means, said automatic means being adapted to engage said frame means whereby to lock or unlock said door.

7. In an elevator structure, a locking mechanism for swing door inclosure units comprising actuating means automatically controlled by a cab control member, means mounted in said inclosure engageable with said actuating means, further means operatively connected with said inclosure means, a draw bolt mounted in the door of said unit normally engaged with said further means and adapted to be moved to control the release of said door by the operation of said actuating means.

8. In an elevator structure, a locking mechanism for swing door inclosure units comprising actuating means mounted upon and automatically controlled by a cab control means, extendible means mounted in the frame of said unit, withdrawable means mounted in the door of said unit, a cam supported upon said inclosure and engaged with said extendible means, said cam being adapted to be engaged and operated by said actuating means whereby to move said withdrawable means to lock or unlock said door.

9. In an elevator structure, a locking mechanism for swing door inclosure units comprising actuating means mounted upon and controlled by a cab controlled means, a draw bolt mounted in the door of said unit a draw bolt operating element mounted with 125 in the frame of said unit and normally in engagement with said draw bolt, means supported upon said inclosure unit and linked with said operating element, said last means being adapted to be engaged and operated by 130

said cab controlled means whereby to actuate said draw bolt to release or lock said door.

10. In an elevator structure, a locking mechanism for swing door inclosure units comprising means mounted upon a cab located within the shaft of said structure, said means being controlled by the control member of said cab, an operating element mounted within the frame of said unit, withdraw-
10 able means mounted in the door of said unit, a cam extending into the shaft of said structure mounted upon said unit and linked with said operating element, said cam being adapted to be engaged and operated by said 15 cab mounted means whereby to move said withdrawable means to release or lock said door.

11. In an elevator structure, a locking mechanism for swing door inclosure units comprising means mounted upon a cab located within the shaft of said structure, said means being automatically controlled by the control means of said cab, a draw bolt mounted in the door of said unit, a draw bolt en-
20 gaging and operating element mounted in the frame of said unit and normally in engagement with said draw bolt, means linked with said operating element, said means being engageable and operable by said cab means, and
25 circuit breaking means in said frame adapted to prevent travel of said cab within said shaft when said door is unlocked.

12. In an elevator structure, a locking mechanism for swing door inclosure units comprising means mounted upon a cab located within the shaft of said structure, said means being controlled by the control means of said cab and by said locking mechanism, a draw bolt mounted in the door of said unit,
30 an operating element mounted in the frame of said unit and normally in engagement with said draw bolt, means releasably connecting said operating element with the means on said cab, said cab means being adapted to actuate said operating element and said draw bolt to lock or unlock said door.

13. In an elevator structure, a locking mechanism for swing door inclosure units comprising solenoid actuated means mounted on a cab located within the shaft of said structure, said means being actuatable by the control means of said cab, a draw bolt in the door of
35 said unit, an operating element in the frame of said unit and normally in engagement with said draw bolt, means releasably connecting said operating element with said solenoid means whereby the operation of
40 said solenoid means controlled from the cab moves to lock or unlock said door.

14. In an elevator structure, a locking mechanism for swing door inclosure units comprising a draw bolt in the door of said unit, a draw bolt operating element in the

frame of said unit and normally in engagement with said draw bolt, a cam mounted on said frame and extending into the shaft of said structure, said cam being linked with said operating element, solenoid actuated means mounted on a cab within the shaft of said structure and adapted to engage and operate said cam whereby to lock or unlock said door.

15. A locking mechanism for swing door inclosure units comprising a draw bolt in the door of said unit, an operating element in the frame of said unit and normally in engagement with said draw bolt, a cam mounted upon said frame, means connecting said cam with said operating element whereby actuation of said cam causes said operating element to releasably engage said draw bolt to permit opening said door.

16. A locking mechanism for swing door inclosure units comprising a draw bolt in the door of said unit, an operating element in the frame of said unit, a cam mounted upon said frame, an arm on said cam, means connecting said arm with said operating element and means in said door adapted to engage and retain said draw bolt in released position during opening or closing of said door.

17. A locking mechanism for swing door inclosure units comprising a draw bolt mounted in the door of said unit, an operating element mounted in the frame of said unit, means in said door engaging and retaining said draw bolt in inoperative position when said door is being opened or closed, said means being released by said operating element, a cam mounted on said frame, means connecting said cam with said operating element whereby actuation of said cam permits or prevents opening said door.

18. A locking mechanism for swing door inclosure units comprising a draw bolt mounted in the door of said unit, an operating element mounted in the frame of said unit, a pivoted arm engageable with said draw bolt when said draw bolt is in released position, a cam mounted on the frame of said unit, means connecting said cam with said operating element whereby when said cam is actuated said draw bolt will be interlocked or releaseably engaged with said operating element to permit or prevent opening said door.

19. A locking mechanism for swing door inclosure units comprising a draw bolt in the door of said unit, an operating element in the frame of said unit, a pivoted arm mounted in said door and engageable with said draw bolt, a cam mounted upon said frame, means connecting said cam with said operating element and circuit control means in said frame adapted to break an electrical contact when said cam is actuated to cause said operating element and said draw bolt to be releasably engaged with each other.

20. In a locking mechanism for swing door inclosure units, a draw bolt in the door of said unit, an operating element in said inclosure and normally interlocked with said draw bolt, a switch box in said inclosure, an arm projecting from said box, said arm being actuated in one direction by said operating element and in the other by said draw bolt.
21. In a locking mechanism for swing door inclosure units, a draw bolt in the door of said unit, an operating element in said inclosure, a switch box in said inclosure, an arm projecting from said box, spaced electrical contacts on said arm, a contact in said draw bolt, said draw bolt contact being adapted, when said door is closed, to engage said spaced contacts whereby to close the circuit of the locking mechanism actuator.
22. In a locking mechanism for swing door inclosure units, a draw bolt in the door of said unit, an operating element in said inclosure, a switch box in said inclosure, means projecting from said box engageable with said operating element and said draw bolt, said means being adapted to open or close one electric circuit when actuated by said element and open or close a further circuit when engaged or released by said draw bolt.

39 In testimony whereof I have affixed my
signature.

LUDWIG G. JACOBSON.
